UNITED STATES PATENT OFFICE.

MICHAEL JUNGLING, OF BOGALUSA, LOUISIANA.

FEED-WATER HEATER FOR LOCOMOTIVES.

1,122,005.

Specification of Letters Patent. Patented Dec. 22, 1914.

Application filed October 10, 1913. Serial No. 794,378.

To all whom it may concern:

Be it known that I, MICHAEL JUNGLING, a citizen of the United States, residing at Bogalusa, parish of Washington, State of Louisiana, have invented a certain new and useful Improvement in Feed-Water Heaters for Locomotives, and declare the following to be a full, clear, and exact description of the same, such as will enable others skilled in the art to which it pertains to make and use the same, reference being had to the accompanying drawings, which form a part of this specification.

My invention has for its principal object to produce a simple and efficient apparatus for conserving a large number of the heat units in the combustion gases of a locomotive and transferring them to the water which is to be transformed into steam in the boiler.

In one of its aspects my invention may be regarded as comprising a simple and efficient feed water heater while in another aspect it may be regarded as comprising means for transferring heat from the combustion gases to the comparatively cool water ordinarily contained in the lower part of the boiler.

A further object of my invention is to produce a novel feed water heating system for locomotive boilers in which the feed water will be heated both by exhaust steam from one or more sources and by the combustion gases. Subsidiary to this object my invention may be regarded as having for a further object the provision of means whereby the feed water may be delivered to the boiler after passing through the exhaust steam heater and either before or after passing through the gas heater.

A further object of my invention is to produce a novel water heater for locomotive boilers which shall take the place and perform the functions of the diaphragm or baffle plate ordinarily arranged in the smoke box.

The various features of novelty whereby my invention is characterized will hereinafter be pointed out with particularity in the claims; but, for a full understanding of my invention and its objects and advantages, reference may be had to the following detailed description taken in connection with the accompanying drawings, wherein:

Figure 1 is a view partly in side elevation

and partly in section showing a fragment of a locomotive equipped in accordance with the present invention; Fig. 2 is a section on line 2—2 of Fig. 1, the top plate or cover of the gas heater being omitted; Fig. 3 is a central vertical section taken lengthwise of the locomotive through the gas heater; and Fig. 4 is a developed plan view of the lower member or half of the gas heater.

Referring to the drawings, 1 represents a locomotive boiler and 2 the extension at the front into which the combustion gases pass before leaving the stack, and ordinarily called the smoke box.

3 is the usual exhaust nozzle arranged in the smoke box below and coaxial with the stack 4.

5 represents one of the cylinders of the locomotives.

All of the foregoing parts may take any usual or preferred forms, the particular forms illustrated being intended simply as conventional representations.

It is common practice to locate in the smoke box a diaphragm or deflector which directs the gaseous products of combustion so as to produce the most desirable draft, the location and the shape of the deflector to-day being the result of years of study and experimentation. In accordance with my invention, I replace the ordinary diaphragm or deflector with a broad, shallow, hollow member, 6, through which the feed water may be passed before entering the boiler so as to take up heat from the combustion gases and make it possible to feed warm water into the boiler without placing in the smoke box anything in addition to the deflector and without departing from the best practice in deflector construction and arrangement. In external appearance the gas heater may resemble a simple thick plate extending transversely of the smoke box and extending in the general direction from the upper rear portion of the smoke box diagonally down toward the lower front end of the smoke box, the heater completely surrounding the nozzle. With this arrangement, the flame and hot combustion gases enter the smoke box below the heater and flow downwardly across the under side of the same, imparting a large amount of heat thereto. In fact, by making the area of the heater great enough substantially all of the hot gases must come in contact with the

hot gases must come in contact with the

under side of the heater and flow along the same in passing from the boiler tubes into the smoke box and thence to atmosphere through the stack.

- 5 The gas heater may be constructed in various ways, although I prefer to make it in the form of a shallow box or pan having a top or cover securely fastened thereto, the main portions of the box or pan having 70
10 therein suitable deflectors or guides which will cause the water passing through the heater to follow a tortuous path which will keep it in contact with the heating surface longer than would be the case if it were allowed to flow in a straight line from the 75
15 inlet to the outlet and also minimizing the possibility of the water becoming pocketed and remaining stationary.

In the arrangement shown, the heater 20 comprises a main or body member, 7, and a cover plate, 8, of any suitable material; the body member 7 being in the form of a shallow box or receptacle having a flat bottom, the central portion of which is horizontal 25 while the rear portion, 9, is inclined upwardly and the front portion, 10, is inclined downwardly. In the center of the horizontal portion of the member 7 is an opening, 11, large enough to permit the passage 30 of the exhaust nozzle, the opening 11 being surrounded by a continuous wall, 12, whose height is just equal to the height of the side and end walls, 13. It is customary to provide the exhaust 35 nozzles with projecting flanges in proximity to the upper ends and therefore when the heater is slipped down over the nozzle it rests upon and its weight is carried by the flange 14 on the nozzle. All of the water 40 which enters the gas heater comes in at the bottom while the water passing out of the heater leaves it at the top.

In the arrangement shown, there are two feed water inlet openings, 15 and 16, arranged in the two side walls of the heater 45 close to the lower end, and there are two outlet openings, 17 and 18, arranged in the two side walls of the heater near the top. Within the interior of the heater between 50 the inlet openings and the delivery openings I arrange a series of transverse deflecting partitions none of which extends completely across the heater, the openings left for the passage of water past the partitions being staggered relative to each other 55 so that the water cannot flow in a straight line. In the particular arrangement shown, the lower inclined portion of the heater has a transverse partition, 19, arranged above 60 the inlet openings and cut away at the center. The front portion of the wall 12 has laterally extending wings, 20, which do not reach quite to the side walls of the heater. Toward the rear of the horizontal portion 65 of the heater are two short partition mem-

bers, 21, 21, extending inwardly from the side walls but not reaching the wall 12. Behind and above the members 21, 21, are two comparatively long partition members, 22 and 23, extending from opposite sides of the heater more than halfway across the same; and between the member 23 and the delivery openings are partition members, 24, 24, extending from opposite sides of the heater toward but not quite to the center. 75 The course of water flowing through the heater from the inlet openings to the delivery openings is indicated by the arrows.

In addition to supporting the gas heater upon the nozzle it may be supported and 80 braced by fastening it in any suitable way to the shell of the smoke box and to the front sheet of the boiler, the body portion of the heater being provided with a perforated flange, 25, to which suitable attaching 85 and bracing devices may be fastened; the arrangement being preferably such that the heater forms a partition extending forwardly and downwardly from the front sheet of the boiler for the full width of the 90 smoke box, so that none of the hot gases can escape without flowing down beneath the lower front edge of the heater.

The inlet openings 15 and 16 of the heater are connected to pipes, 30 and 31, each of 95 which is supplied with feed water in any suitable way. The delivery openings 17 and 18 are connected to the interior of the boiler by means of valved pipes, 32 and 33. In accordance with one feature of my invention I also connect the lower portion of the heater with the lower portion of the boiler where the water is usually cool as compared with the water from which the steam is being evolved. In the arrangement shown, I 100 have provided a separate valved pipe, 34, between the lower end of the heater and the bottom of the boiler, the pipe containing also a check valve, 35, which will prevent the water from flowing through the connection toward the boiler. The pipe 34 may conveniently be connected with the pipe 30 just before the latter pipe enters the shell 105 of the smoke box, thus bringing the pipe 34 and its valves outside of the smoke box. 110

With the arrangement described feed water can be delivered to the boiler from either or both injectors, first passing through the heater and having its temperature raised so that it enters the boiler as 115 hot water. Furthermore, there may at all times be a circulation of water from the bottom of the boiler through the heater and back into the top of the boiler so that even when the locomotive is standing still and 120 no water is being delivered to it, some of the heat of the combustion gases will be utilized to heat the comparatively cool water in the bottom of the boiler.

All locomotives are now equipped with 130

air pump the exhaust steam of which is wasted, usually being blown out of the stack. This is a disadvantage not only because of the loss of the heat units in the exhaust steam, but also because it frequently happens upon starting the air pump while the locomotive is standing in a station that the exhaust steam discharged through the stack collects soot and therefore emerges in the form of a fine black spray which is very objectionable particularly when it rains upon persons in the vicinity of the locomotive. For the purpose of overcoming the objections noted in connection with the operation of the air pump, I have provided an exhaust steam heater, 40, which is preferably a closed steam heater of any suitable type mounted at any convenient point upon the locomotive and having an inlet pipe, 41, which receives the exhaust steam from the air pump. The feed water from one of the injectors may be carried into the heater 40 through the pipe 42, the discharge end of the heater being connected to the pipe 30 which is one of the supply pipes for the gas heater. The heater 40 is provided with a suitable discharge pipe, 43, for steam which is not condensed in the heater and with a suitable drip pipe, 44, through which the water of condensation may be discharged. In addition to the steam from the air pump the exhaust steam heater may also receive steam from the main cylinders of the engine; a connection, 45, between the heater 40 and the exhaust side of the engine cylinders being provided for this purpose.

The pipes 30 and 32 are connected by a valved branch pipe 46 and between the pipe 46 and the heater 40 is arranged a check valve, 47, which will prevent back flow of water from the boiler. When the valve in the pipe 46 is closed and the injector is started, the feed water will flow through the exhaust steam heater 40, through the gas heater 6 and then to the boiler.

When it is desired to cut out the gas heater, valves 48 and 49 arranged respectively in the pipe 30 and in the pipe 32 between the branch 46 and the gas heater are closed and the valve in the pipe 46 is opened. The feed water will now flow directly from the exhaust steam heater through the branch pipe 46 and into the boiler without going through the gas heater.

It will thus be seen that I have provided a simple and novel arrangement for simultaneously controlling the flow of the gaseous products of combustion and transferring a large part of the heat content therein to feed water for the boiler and have also provided a simple arrangement for utilizing the exhaust steam from the air pump for the purpose of heating feed water and at the same time overcoming the objectionable feature of a wet sooty discharge from the

smoke stack when the air pump is started. It will also be seen that I have provided a simple arrangement for connecting the exhaust steam in the gas heaters in series for permitting the gas heater to be disconnected if desired. It will also be seen that I have provided a simple and effective means for producing a circulation of the water in the boiler and transferring heat from the gaseous products of combustion and flame to the cool water in the bottom of the boiler.

While I have illustrated and described with particularity only a single preferred form of my invention I do not desire to be limited to the exact structural details thus illustrated and described; but intend to cover all forms and arrangements which fall within the terms employed in the definitions of my invention constituting the appended claims.

I claim:

1. The combination with the smoke box of a locomotive boiler, of a flanged exhaust nozzle projecting upwardly in the box, a diagonal baffle plate or diaphragm extending diagonally from the upper rear portion of the box past the nozzle toward the lower front portion of the box, said baffle plate having an opening therethrough to permit the passage of the nozzle and permit the baffle plate to rest upon the flange of the nozzle, said baffle plate being made hollow so as to provide a long wide shallow chamber in the interior thereof, a feed-water supply pipe connected to said chamber, and a feed-water delivery pipe extending from the chamber to the interior of the boiler.

2. The combination with the smoke box of a locomotive boiler, of a diagonal baffle plate or diaphragm in the smoke box having a long wide shallow chamber in the interior thereof, a feed-water supply pipe connected to the lower end of said chamber, a feed-water delivery pipe extending between the upper end of said chamber and the boiler, and a series of deflecting plates arranged in said chamber for causing the water flowing through the same to follow a tortuous passage.

3. In combination, a locomotive boiler having a smoke box, a flanged exhaust nozzle projecting upwardly in the box, a baffle plate or diaphragm extending diagonally from the upper rear portion of the box toward the flange of the nozzle and then continuing forward in a horizontal direction, the horizontal portion of the baffle plate having an opening therethrough to permit the baffle plate to rest upon the flange of the nozzle, said baffle plate being made hollow so as to provide a long wide shallow chamber in the interior thereof, an outlet from the upper end of said chamber to the boiler, and an inlet for delivering feed-water to the chamber.

4. The combination with the smoke box of

- a locomotive boiler, of an exhaust nozzle projecting upwardly in the box, a broad shallow hollow deflector surrounding the nozzle, said deflector having a water inlet at the 5 bottom, a delivery pipe between the upper end of the deflector and the boiler, and means in the interior of the deflector for causing water flowing through the same to follow a tortuous passage.
- 10 5. The combination with a locomotive boiler having a smoke box, of a feed-water heater in the smoke box, an exhaust-steam feed-water heater outside of the boiler, means for passing feed water into the boiler 15 through said heaters in series, and a by-pass leading into the boiler from a point between said heaters.
6. The combination with the smoke box of a locomotive, of a water heater in the 20 smoke box in the path of the combustion gases, conduits connecting the upper and lower ends of the heater to corresponding
- points in the boiler, and a water supply pipe connected to the lower end of the heater.
7. The combination with the smoke box 25 of a locomotive boiler, of an exhaust nozzle projecting upwardly in the box, of a diagonal baffle plate or diaphragm extending transversely across the smoke box from the upper rear portion of the box past the nozzle 30 toward the lower front portion of the box, said baffle plate or diaphragm having an opening therethrough to receive the nozzle, and being made hollow so as to provide in the interior thereof a long wide shallow 35 chamber, means for supplying water to said chamber, and a connection between said chamber and the boiler.

In testimony whereof, I sign this specification in the presence of two witnesses.

MICHAEL JUNGLING.
